(57) **CLAIM**

The ornamental design for a golf club head, as shown and described.

DESCRIPTION

FIG. 1 is a bottom perspective view of a golf club head showing my new design;

FIG. 2 is a bottom view thereof;

FIG. 3 is a rear view thereof;

FIG. 4 is a toe end view thereof;

FIG. 5 is a heel end view thereof;

FIG. 6 is a front view thereof; and,

FIG. 7 is a top view thereof.

The uneven broken lines are shown for the purpose of illustrating environmental structure and form no part of the claimed design.
